UNITED STATES PATENT OFFICE.

JOHN H. CHENOWETH, OF CHICAGO, ILLINOIS.

FREIGHT-CAR DOOR.

1,199,049.

Specification of Letters Patent. Patented Sept. 26, 1916.

Application filed September 22, 1913. Serial No. 790,979.

To all whom it may concern:

Be it known that I, JOHN H. CHENOWETH, a citizen of the United States, residing at Chicago, in the county of Cook and State 5 of Illinois, have invented certain new and useful Improvements in Freight-Car Doors, of which the following is a full, clear, and exact description, reference being made to the accompanying drawings, forming a part 10 of this specification.

My invention relates to freight cars, and has been more especially designed for use in connection with refrigerator cars which employ doors of considerable thickness.

15 My present invention employs and embodies the broad structural principle disclosed in my former Letters Patent No. 801,439, granted to me October 10, 1905, but presents several modifications of and improvements upon the structure disclosed in the aforesaid Letters Patent which latter adapts the broad principle of the said structure to refrigerator or other cars having bodily movable sliding doors of considerable 25 thickness.

Among the leading objects attained by the invention are, first, the provision of a novel door-actuating mechanism for shifting the door into and out of the door opening, after 30 a greater extent or range of bodily movement than has heretofore been possible; the provision of a novel and effective means for holding the door-hangers against turning movement during the outward and inward movement of the door relatively to the door opening; the provision of means for effecting a final powerful inward pressure by the door to force it into snug and substantially air-tight engagement with the 35 door jamb; and the provision of a device in the nature of a guide for limiting and controlling the outward swinging movement of the lower end of the door.

Other minor objects and improvements secured by the invention will be apparent from the following detail description, taken in connection with the accompanying drawings which illustrate an improved embodiment of my invention, and in which—

45 Figure 1 is a side elevation of a portion of the side of a car-body showing my improved door in closed position. Fig. 2 is a vertical cross section on the line 2—2 of Fig. 1. Fig. 3 is a horizontal cross section, enlarged, on 50 the line 3—3, Fig. 1. Fig. 4 is an enlarged vertical section through the door opening,

showing the door in edge elevation and in open position. Figs. 5 and 6 are enlarged details, in horizontal section, illustrating, in idle and operative positions, respectively, a 60 device for effecting a final powerful door-closing movement to insure the snug seating of the door in the door jamb or casing.

Referring to the drawings, 10 designates the side wall of the car, in which is formed 65 a door opening 11, preferably of the stepped form shown, which is usual in refrigerator doors to secure a more perfect and airtight joint. Directly above the door opening 11 is secured a running track 12.

13 designates the door which, as will be seen by reference to Fig. 4, is of considerable thickness and the edge of which is of a stepped form to coöperate with the stepped opening 11. Mounted vertically in upper 70 and lower bearings 14 and 15 on the outer face of the door 13 are a pair of crank shafts 16. On the upper ends of the crank shafts 16 are cranks 17, the vertical stems 18 of which are journaled in a pair of door 75 hanger brackets 19, these latter carrying wheels 20 that engage the fixed track 12. The crank stem 18 is secured in its bearing 19 by a cotter pin 21 and washer 22. The weight of the door 13, when in open position, is supported by the hanger brackets 19, through the crank shafts 16, by means 80 of collars 23 fast on the crank shafts 16 engaged by the upper bearings 14. To prevent any turning or twisting tendency of 85 the hanger brackets 19 during the operation of moving the door inwardly and outwardly of the opening, I provide a distance rod 24 which, at one end, is secured in one of the hanger brackets, conventionally as by a 90 threaded engagement therewith, as shown at 25 in Fig. 1, while its opposite end has a sliding engagement in a bearing 26 on the other hanger bracket. This rod 24 serves in an obvious manner to lock the two hanger 100 brackets against turning or twisting upon the track 12 in the half turning movement given to the crank shafts 16 in opening and closing the door, as hereinafter described.

Since, in practice, it is difficult and virtually 105 impossible to insure the perfect parallelism of the crank arms 17 in all positions of the shafts 16, it is highly desirable to provide the described sliding fit of the distance rod 24 with one of the hanger brackets to accommodate the slight to-and-fro movements 110 of said hanger brackets relatively to each

other that occur during the actuation of the door.

To the lower ends of the crank shafts 16 are keyed or otherwise secured spur pinions 27 preferably housed by downward extensions 15' of the lower bearings 15. To save space, the outer face of the door 13 is provided with shallow mortises 28 (Fig. 4) to accommodate the pinions 27, and permit the shafts 16 to lie close to the outer face of the door. Slidably mounted in and between the extensions 15' is a bar 29, best shown in Fig. 3, the outer end portions of which are outwardly offset, as shown, and carry racks 30 engaging the pinions 27. To the rack bar 29 is pivoted a link 31, forming a connection between said rack bar and one end of an operating lever 32, which latter is fast upon a stud 33 (Fig. 2) journaled in a bushing 33' in the door. The lever 32 terminates in a handle 34 and, in the closed position of the door, is locked by a guide 35 secured to the face of the door co-operating with a loop 36 on the lever 32 and a keeper 37.

The door is locked in closed position and simultaneously at its lower end is drawn tightly into engagement with the edge of the door opening by means of a pair of locking bars 38 slidably mounted in keepers 39 on the inner face of the door, said locking bars being pivotally connected at their inner ends to and at diametrically opposite points on a crank disk 40 integral with or fast on the inner end of the stud shaft 33. The outer ends of the locking bars 38 are bent outwardly slightly relatively to the door, as shown at 38' in Fig. 3; and, when in locking position, slidably engage wedge-shape cam blocks 41 secured to the inner side of the wall 10 of the car adjacent to the opposite vertical edges of the door opening. The operative relation of the crank disk 40 and locking bars 38 to the actuating mechanism of the crank shafts 16 is such that when the latter are actuated to move the door outwardly of the opening the locking bars 38 are retracted, and, when the crank shafts 16 are actuated to move the door into closed position, the locking bars 38 are forced outwardly into the locking position shown in Figs. 1 and 3.

To steady the lower end of the door and prevent undue widthwise or edgewise oscillation thereof in operating the same, I provide a headed keeper-rod 42 that is slidably mounted in a bearing 43 secured to the face of the door at the lower end of the latter, the lower end of the keeper-rod 42 being secured to a sleeve member 44 that slidably engages a fixed guide-rod 45 in turn secured to the side wall 10 of the car, said guide-rod being of sufficient length to accommodate the full edgewise travel of the door to fully expose the door opening.

46 and 47 designate a pair of stops secured to the side 10 of the car at proper positions to engage the ends of the distance rod 24 when the door is at the precise extremes of its travel.

48 designates a wear-strip secured to the side wall of the car on that side of the door opening over which the door operates to prevent injury to the side wall of the car by reason of chafing or abrasion of the door against the latter.

49 designates a handle secured to the face of the door near its lower end, by means of which the operator, when actuating the lever 34 to unlock the door and force outwardly its upper end, may, simultaneously, assist the action of gravity by pulling outwardly upon the lower end of the door in case the latter tends to stick in the opening.

50 designates a fixed stop on the door designed to limit the swing of the lever 32.

The final inward movement of the door and the initial outward movement thereof are facilitated and a tight joint obtained by an auxiliary closing and opening device best shown in detail views Figs. 5 and 6, and comprising a lug or spur 51 on the upper end of each crank-shaft 16 opposite and extending at right angles to the crank-arm 17, which lug, as the door approaches the fully closed position, comes into sliding engagement with a cam-shaped lug or keeper 52 formed on a plate 52' that is secured to the side wall 10 just above the door opening. This device takes the strain of the final closing movement off the hanger brackets and affords a short-arm resistance lever which has the effect of increasing, at this point, the power leverage of the operating lever 32. In the initial opening movement, the outer edge of the lug or spur 51 strikes and wipes over the plate 52', thus creating an initial outward thrust and affording an increased leverage (as compared with that of the crank-arm 17) to overcome any tendency of the door to stick in the opening. It is understood that there is sufficient lateral play of the hanger brackets 19 relatively to the track 12 to permit the above described action.

The door is shown in Figs. 1 and 2 in its closed and locked position. To open the door, the keeper 37 is withdrawn, and the lever 32 swung to the left until it engages the stop 50. This retracts the locking bars 38; and, simultaneously, through the bar 29, rack bars 30 and pinions 27, imparts a full half revolution to the crank shafts 16. As the latter are journaled eccentrically at their upper ends in the hanger brackets 19, this results in an outward movement of the upper end of the door to an extent equal to twice the length of the cranks 17, which is ample to completely offset the door relatively to the outer plane of its opening, as

shown in Fig. 4. During the initial part of this opening movement the lugs 51 strike and wipe over the plates 52' and impart an initial outward thrust on the upper end of the door independently of the cranks 17 in the manner described. The lower portion of the door at the same time swings outwardly under the force of gravity, assisted by a pull on the handle 49, if necessary.

10 During this operation the distance rod 24 prevents turning of the hanger brackets 19 and insures the correct alinement of the trolley wheels 20 upon the trolley track 12. The door is then pushed edgewise to the

15 right until the end of the distance rod 24 engages the stop 47, when the opening 11 is fully exposed. During this edgewise movement of the door the headed keeper-rod 42 effectively prevents any edgewise oscillation

20 of the door and limits the sidewise oscillation of the lower end of the door to substantially the vertical position. The car having been loaded, the door is pushed edgewise back to a position directly in front of the

25 opening, which is determined by the engagement of the other end of the distance-rod 24 with the stop 46. The lower end of the door is then pushed inwardly, and simultaneously the lever 32 is swung to the position shown in Fig. 1, which reverses the direction of rotation of the crank shafts 16, and forces the upper end of the door into closed position. During the final part of this turning movement of the crank shafts

30 16, the spurs 51 come into engagement with the cam lugs or keepers 52 and increase the effectiveness of the final part of the closing movement of the operating lever 32 in the manner already described. The lock or

35 keeper 37 may then be reengaged with the end of the guide 35 to secure the lever 32 in normal position, whereupon the door is fully closed and locked.

In the door-operating mechanism disclosed in my former Patent No. 801,439, above referred to, it was possible to give to the crank shafts only a quarter turn, which considerably limited the extent of outward bodily movement of the door relatively to its opening, and hence rendered the operating mechanism of that patent impractical for thick doors such as those of refrigerator cars. By my present operating mechanism, it is possible to give to the crank shafts a full half turn, which doubles the extent of bodily outward movement of the door, as compared with my former patent, and hence, in effect, doubles the thickness of door which may be employed.

60 I claim:—

1. In a freight car construction, the combination with the car-side having an open-

ing, of a door, vertical crank shafts journaled upon the door, cranks on the upper ends of said crank shafts having vertical stems, a track mounted on the car-side above the door opening, hanger brackets having wheels engaging said track and further provided with bearings for said crank stems, a rod secured to one of said brackets and having a sliding engagement with the other, and means for effecting a turning movement of said crank shafts.

2. In a freight car construction, the combination with the car-side having an opening, of a door, vertical crank shafts journaled upon the door, cranks on the upper ends of said crank shafts having vertical stems, a track mounted on the car-side above the door opening, hanger brackets having wheels engaging said track and further provided with bearings for said crank stems, 70 pinions on said crank shafts, a rack bar slidably mounted on said door and engaging said pinions, and means for imparting endwise movement in either direction to said rack bar.

3. In a freight car construction, the combination with the car-side having an opening, of a door, vertical crank shafts journaled upon the door, cranks on the upper ends of said crank shafts having vertical stems, a track mounted on the car-side above the door opening, hanger brackets having wheels engaging said track and further provided with bearings for said crank stems, 90 coöoperating lugs on said crank shafts and the car-side, respectively, adapted to come into cam engagement with each other when the door is in nearly closed position, and 95 means for imparting a turning movement to said crank shafts.

4. In a freight car construction, the combination with the car-side having an opening, of a door, vertical crank shafts journaled upon the door, cranks on the upper ends of said crank shafts having vertical stems, a track mounted on the car-side above the door opening, hanger brackets having wheels engaging said track and further provided with bearings for said crank stems, 105 wear-plates carrying cam-lugs secured to the car-side above said opening, laterally projecting lugs on said crank shafts, respectively, adapted to engage said cam-lugs during the final part of the closing movement of the door and to engage said wear-plates 110 during the initial part of the opening movement of the door, and means for imparting a turning movement to said crank shafts.

JOHN H. CHENOWETH.
